EXTENSIBLE CONVEYORS

Roy F. Lo Presti and John R. Madeira, Chicago, Ill., assignors to Goodman Manufacturing Company, Chicago, Ill., a corporation of Illinois

Application May 25, 1956, Serial No. 587,320

8 Claims. (Cl. 198—139)

This invention relates to improvements in extensible belt conveyors of the type where the conveying reach is supported upon spaced flexible strands, and more particularly to improvements in such a conveyor whereby the troughing action of the idler assemblies may be had at a movable end section of such conveyor, and whereby additional troughing roller assemblies may be placed readily in position at the outby end of the tail section of such conveyor.

In Craggs et al. applications Serial Nos. 548,622 and 549,603, filed November 23 and November 29, 1955 respectively, for Extensible Conveyors, the flexible strands supporting the load carrying reach of the endless belt are reeved upon a storage reel mounted to the sides of the inby or tail section.

According to the present invention, the flexible strands for the troughing rollers are guided at the inby or tail section along the inner face of the side frames, and are reversed in direction at a point extremely close to the inby end thereof, the reversed strand being then trained in an outby direction and wound upon the conventional storage reel. The troughing roller assemblies in such cases can, as with the length of the strands between the head and tail sections, be supported upon that portion of the strands extending longitudinally of the tail section.

As the strand is payed out by movement of the conveyor in an extending direction, the troughing roller assemblies can be held against movement with the strands by hangers therefor which enclose the strand and held between spaced abutments upon the side frames, so that the strands may slide through the hangers upon such extending movement of the conveyor.

According to the present invention there is substantially no bending of the support strands adjacent the outby end of the tail section, and it is therefore possible during the extending movement to mount a troughing roller assembly immediately outby of the tail section.

One of the principal objects of this invention is to provide an improved extensible belt conveyor characterized by a tail section with flexible strands extending for the length thereof, together with troughing roller assemblies which are disposed along the length of the tail section and suspended from such flexible strands.

Other objects and important features of the invention will be apparent from a study of the specification following taken with the drawings which together describe and illustrate a preferred embodiment of the invention and what is now considered to be the best mode of practicing the principles thereof. Other embodiments may be suggested to those having the benefit of the teachings herein and such other embodiments are intended to be reserved especially as they fall within the scope and purview of the subjoined claims.

In the drawings:

Fig. 1 is a plan view of the tail section of an extensible conveyor having the improvements according to the present invention embodied therein;

2

Fig. 2 is an elevational view of one of the troughing roller assemblies supported upon the flexible strands extending longitudinally of the tail section seen in Fig. 1;

Fig. 3 is a detailed plan view of a portion of the troughing roller assembly seen in Fig. 2, showing details of means mounted to the side frames of the tail section seen in Fig. 1 for preventing shifting of the assembly on the flexible strands; and

Fig. 4 is a section taken along the line 4—4 of Fig. 10 1 looking in the direction of the arrows, certain parts being shown in elevation, showing means for reversing the flexible support strands at the inby end of the tail section.

Referring now to Fig. 1 of the drawings there is shown 15 an extensible conveyor indicated generally by the reference numeral 10 and including an inby or tail section 11 having spaced side frames 12, the inby or tail section 11 being mounted for movement upon endless crawler treads 13. As seen in Fig. 1, the spaced side frames 12 are maintained in spaced relationship by means of laterally extending members 14 and 16.

The extensible conveyor 10 has an endless belt consisting of a conveying reach 17 and a return reach 18, the two reaches being reversed in direction about an 25 idler pulley 19 mounted on a shaft 21 disposed at the inby end of the tail section 11.

The conveying reach 17 is supported upon spaced flexible strands 22 which are spanned by troughing roller 30 assemblies indicated generally by the reference numeral 23, details of such assemblies being as shown in Craggs et al. application Serial No. 521,355, filed July 11, 1955 for Rope Frame Conveyor and Troughing Roller Assembly Therefor. As disclosed in said application, the flexible strands 22 are supported at intervals throughout their 35 length upon standards 24 and each such standard includes an idler 26 for support of the return reach 18.

According to the present invention the flexible strands 22 extend to a point adjacent the inby end of the tail section 11 and are reversed in direction around an idler 40 sheave 27, the end of the strand being wound upon a storage reel or drum 28. Power means, not shown, is provided for imposing suitable tension upon the strand 22 so as to support the conveying reach 17.

Referring now to Fig. 4 of the drawings, the idler 45 sheave 27 is mounted upon a bearing pin 29 held in a block 31 welded to the inner sides of the side frames 12.

That portion of the flexible support strand extending 50 for the length of the tail section 11 is arranged to support also that portion of the conveying reach 17 extending for the length of such tail section 11, and troughing roller assemblies indicated generally by reference numeral 23A extend laterally of the support strands 22 for such purpose.

Referring now to Fig. 2 of the drawing, each of said 55 troughing roller assemblies 23A consists of a center load supporting roller 32 flanked by wing rollers 33. Each of the rollers 32 and 33 includes a shaft 34, and the ends of the shaft adjacent to each other are connected by a link 36 having a pin connection 37 at each end thereof 60 to the ends of the shaft 34, so that the rollers 32 and 33 may move articulately in a vertical plane.

The outer ends of the shafts 34 of the wing rollers 33 are connected by a link 38 having a pin connection 39 65 at one end to the outer end of the shaft 34 and a pin connection 41 to a bracket 42 extending inwardly of a tubular sleeve 43.

The tubular sleeve 43 is threaded by the support strand 22 as seen more particularly in Figs. 2 and 3, and the 70 entire assembly consisting of the rollers 32, 33 and the tubular sleeve 43 are held against shifting longitudinally between a pair of spaced angle brackets 44 having their

feet held to the side frame 12 as by means of cap screws 46.

As seen in Fig. 2 each of the angle brackets 44 is provided with a T-slot 47 which permits entrance of the support strand 22, the head of the T-slot being inclined as seen in Fig. 2 for movement of the strand 22 along the axis of such head of the T-slot as is occasioned by changes in load upon the conveying reach 17 and the strand 22.

As seen in Fig. 1, the outby end of the tail section 11 is provided with an eye guide 48 through which each of the strands 22 extend. It will be noted that each strand 22 is bent but through a very small angle, and for all practical purposes may be considered as deforming the strand only to the amount as would be had at the support standard 24 next outby of the tail section 11.

From the foregoing description it will be noted that substantially the same type of troughing roller assembly can be provided for the tail section, and that the positions of such troughing roller assemblies at the tail section are unchanged during the change in length of the conveyor. Moreover, after the conveyor has been extended a desired amount, troughing roller assemblies like those marked with the reference numeral 23 can be placed in position close to the inby section, or if desired, as the conveyor extends a support standard 24 may be placed closely adjacent the outby end of the tail section 11.

While the invention has been described in terms of a preferred embodiment thereof its scope is intended to be limited only by the claims here appended.

We claim as our invention:

1. In an extensible conveyor of the type including a pair of flexible strands for support of the conveying reach of an endless belt, a movable section including means for trammimg said section, a pulley on said movable section adjacent the end thereof for reversing said conveying reach, means training said strands along said movable section and reversing same, means for storing the reversed length of said strand comprising a storage reel, at least one troughing roller assembly supported by said strands along said movable section, and means for restraining movement of said troughing roller assembly with respect to said section while said strand moves with respect to said section comprising spaced abutments on said movable section.

2. In an extensible conveyor of the type including a pair of flexible strands for support of the conveying reach of an endless belt, a movable section including means for trammimg said section, means at said movable section for reversing said conveying reach, means training said strands along said movable section and reversing same, means for anchoring the reversed length of said strand, at least one troughing roller assembly supported by said strands along said movable section, and means for restraining movement of said troughing roller assembly with respect to said section while said strand moves with respect to said section comprising spaced abutments on said movable section.

3. In an extensible conveyor of the type including a pair of flexible strands for support of the conveying reach of an endless belt, a movable section including means for trammimg said section, means at said movable section

for reversing said conveying reach, means training said strands along said movable section and reversing same, means for storing the reversed length of said strand, at least one troughing roller assembly supported by said strands along said movable section, and means for restraining movement of said troughing roller assembly along said strand when said strand moves with respect to said section.

4. In an extensible conveyor of the type including a pair of flexible strands for support of the conveying reach of an endless belt, a movable section including means for trammimg said section, means at said movable section for reversing said conveying reach, means training said strands along said movable section and reversing same, means for anchoring the reversed length of said strand, at least one troughing roller assembly supported by said strands along said movable section, and means for restraining movement of said troughing roller assembly when said strand moves with respect to said section.

5. In an extensible conveyor of the type including a pair of flexible strands for support of the conveying reach of an endless belt, a movable section, means training said strands along said movable section, at least one troughing roller assembly supported by the said strands trained along said movable section, and a sliding connection between said strands and said troughing roller assembly whereby said strands can move with respect to said troughing roller assembly.

6. In an extensible conveyor of the type including a pair of flexible strands for support of the conveying reach of an endless belt, a movable section, means training said strands along said movable section, at least one troughing roller assembly supported by the said strands trained along said movable section, and means for restraining the movement of said troughing roller assembly while said strands move with respect to said movable section.

7. In an extensible conveyor of the type including a pair of flexible strands for support of the conveying reach of an endless belt, a movable section, means training said strands along said movable section, at least one troughing roller assembly supported by the said strands trained along said movable section, and means whereby said strand is movable relative to said troughing roller assembly while said troughing roller assembly is maintained in a fixed position relative to said movable section.

8. In an extensible conveyor of the type including a pair of flexible strands for support of the conveying reach of an endless belt, a movable section, means training said strands along said movable section, at least one troughing roller assembly supported by the said strands trained along said movable section, and means for restraining movement of said troughing roller assembly along said strands comprising abutments on said movable section against which said troughing roller assembly bears.
